PLATE CLAMP

Charles W. Harrold, University Heights, and Earl W. Curtis, Maple Heights, Ohio, assignors to Harris-Seybold Potter Company, Cleveland, Ohio, a corporation of Delaware

Application October 9, 1942, Serial No. 461,414

16 Claims. (Cl. 101—415.1)

This invention relates to plate clamps, that is to say means for clamping the ends of a plate onto one of the elements of a printing couple. Primarily the invention has to do with means for clamping and tensioning a plate on the plate cylinder of a lithographic or gravure printing press, the cylinder being provided with a gap in which the plate clamp is positioned radially inward of the cylinder surface.

One of the objects of the invention is the provision of simple means for gripping the ends of a plate. Another object is the provision of plate clamping means occupying a relatively small space.

Another object is the provision of operating means which functions to actuate the plate gripping means and thereafter to move the clamp assembly for exerting a pull to draw the plate tightly against the cylinder wall.

Other objects and features of novelty appear as we proceed with the description of those embodiments of the invention which, for the purposes of the present application, we have illustrated in the accompanying drawings, in which

Fig. 1 is a plan view of a plate cylinder embodying a plate clamp constructed in accordance with the invention.

Figs. 2 and 3 are fragmental cross-sectional views on a larger scale, taken substantially along the lines 2—2 and 3—3 of Fig. 1, and showing a plate in operative position.

Fig. 4 is a fragmental cross-sectional view on a still larger scale showing details of one of the clamp assemblies.

Fig. 5 is a side elevational view of one of the clamping bars.

Fig. 6 is a bottom plan view of the same.

Fig. 7 is a fragmental perspective view of one of the assemblies.

Fig. 8 is a detail perspective view of one element of the operating or adjusting means.

Fig. 9 is a fragmental plan view of a modified form of the invention, and

Fig. 10 is a cross-sectional view taken substantially on line 10—10 of Fig. 9.

Referring first to Figs. 1 to 8 inclusive, a plate cylinder of usual construction is shown at 10. It is provided with a gap 11, which is also of usual form. The plate clamp, which constitutes the subject of the invention, is mounted in this gap. One end of the plate, which is marked 12, is secured within a single assembly comprising an elongated housing 13. The other end is preferably mounted in three separate assemblies, each of which comprises a housing 14.

The housing 13 and the housings 14 are arranged to slide on the bottom surface of the gap toward and away from each other. They are held against movement away from the bottom surface of the gap by means of retainer plates 15 and 16. Each retainer plate 15 is formed to engage the outer surface of housing 13 as well as the outer surfaces of two adjacent housings 14 being anchored in the cylinder between the two 5 housings by screws 17 or the like which extend through spacing sleeves indicated at 18. The end retaining plates 16, each of which engages but one housing 14, are similarly mounted by means of screws 19 and spacers 20. Additional mounting means for the latter comprises for each plate a screw 21 that projects through a short spacing sleeve 22 which rests upon a block 23. Screw 21 extends through a hole in the block into the threaded opening in the cylinder, as shown in 10 Fig. 3. The opposite end of block 23 is anchored by a screw 24 which extends through the block into a threaded opening in the cylinder, as also shown in Fig. 3.

The housing 13 is provided with a longitudinal groove 25. The sides of this groove as shown are planar surfaces and are preferably parallel, the upper side 26 being narrower than the bottom side because of the necessity for clearing the path of the cylinder surface as the cylinder rotates. The plate 12 is gripped between this groove wall 26 and a clamping bar 27 which is mounted in the groove and is capable of being rocked transversely, as by means of a pin wrench (not shown) inserted into one of the end holes 28 through the bar. By means of such a wrench the bar 15 may be tilted or rocked transversely.

As illustrated specifically in Figs. 4 and 7 the upper and lower surfaces 29 and 30 respectively of the bar are cam shaped, the surface 29 being provided preferably with longitudinal serrations 31 for better gripping action. These surfaces 29 and 30 are so arranged and proportioned with respect to the width of the groove 25 that when the bar is rocked in the anti-clockwise direction, as viewed in Figs. 2, 4 and 7, a line joining the high spots of the two cam surfaces will move toward the vertical, thereby tending to wedge the bar between the side walls of the groove 25. As will be apparent also, this wedging action is promoted or enhanced by any force tending to pull the plate out of the clamp, that is toward the left in Figs. 2, 4 and 7. The gripping of the plate end may be accomplished by rocking the bar 27 20 by means of a pin wrench, as above mentioned,

although we prefer to do so by other means, as will be presently described.

When the force tending to hold bar 27 in its plate gripping position is relieved, it is desirable to have the bar rock clockwise automatically so as to release the plate end. This may be accomplished by means of a coil spring 32 which seats against a screw plug 33, the head of which is threaded into a threaded socket in the top of the housing 13. The lower end of this spring seats in a pocket 34 formed in a lateral extension 35 of bar 27. This extension may be conveniently formed with a round shank 36 which may be driven into a suitable hole in the bar. Any desired number of these spring assemblies may be employed, two being shown herein. In order to accommodate the bar extensions 35 and the springs 32, the housing 13 must be provided at the proper points with cavities 37 opening into the groove 25.

In this form of the invention we provide common operating means for first rocking the clamping bar 27 toward plate gripping position, which is the position illustrated in the drawings, and thereafter for pulling the clamping assembly, that is the housing 13 and the bar 27, away from the adjacent wall 38 of the cylinder gap. The operating means for this assembly may comprise two or more units, three being illustrated herein. Each such unit comprises a screw 40 provided with a head 41 having radial holes 42 therein for the reception of a pin wrench in order to facilitate manipulation. This screw projects through an internally threaded sleeve 43 which is slidably mounted in a smooth hole 44 in the housing 13 and extends through an arched opening in the bar 27, like the opening 45 in Figs. 5 and 6. At its outer end this sleeve has a head 46 with laterally extending wings which are received in a cavity 47 in the outer side of bar 27 and which engage curved surfaces 48 at the bottom of the bar, tending to turn the bar in the plate gripping position against the action of springs 32, that is when a pull is exerted upon the sleeve in a direction toward the right as seen in Figs. 4 and 7. While the screw 40 may be made in one piece if desired, we prefer to form the inner end of a separate hardened steel plug 49 having a shank freely fitted into an axial hole in the end of the screw proper. When the screw 40 is threaded into the sleeve 43 the plug 49 is caused to engage the wall 38 of the gap, after which it remains stationary while the screw turns. Continued turning of the screw in the same direction causes the head 46 of sleeve 43 to pull against the curved surface 48 of bar 27, thereby rocking the bar into plate gripping position. As soon as the bar is tightly wedged against the plate and can turn no further, additional operation of the screw 40 exerts a pull through bar 27 upon the housing 13, and the entire assembly then moves toward the right.

Each of the three sections of the clamp on the side opposite the housing 13 and bar 27 functions in the same way as the assembly already described, except that there is but one operating means for each section and but one spring assembly for rocking the bar away from gripping position. The clamping bars 50 are identical, each being provided with a single hole 51 for the reception of a pin wrench, and the bar 52 is the same except that its hole 53 is at the right end of the bar rather than at the left, as seen in Fig. 1.

Between each of the housings 14 and the housing 13 there are interposed two compression

springs 55, the ends of which set into sockets in the respective housings. When the screws 40 are backed off, the springs 55 push the housings outward as far as they will go.

When the two ends of the plate 12 are in the bite or the clamp, the plate may be adjusted lengthwise of the roller. For this purpose we mount in the ends of the housing 13 two adjusting screws 56. The heads of these screws are caused to bear against the adjacent ends of the gap in the cylinder to fix the longitudinal position of the housing, and when the latter needs to be moved one way or the other one of the screws 56 is turned toward the right and the other toward the left a corresponding amount. The outer extremities of the two end housing 14 are threaded to receive screws 57 which project through slots 58 in blocks 23, and the heads of which bear against washers 59. When it is desired to adjust this end of the plate longitudinally of the cylinder in one direction or the other, one of the screws 57 is loosened and the other screw is then threaded inwardly to exert a pull upon the adjacent housing 14, and through the plate itself upon the remaining housings 14. When the desired adjustment is attained the first screw 57 is then tightened so that the plate end is held in the desired position.

When a plate is to be removed and another plate mounted on the cylinder, the operator first loosens all of the screws 40, permitting the springs 33 to rock the clamping bars to non-gripping position and permitting the springs 55 to push the housing 13 and the housings 14 outwardly against the side walls of the gap. The plate may then be removed. One end of a new plate is then inserted between the clamping bar 27 and the groove wall 26 of housing 13, after which the screws 40 for that housing are threaded outwardly far enough to cause the plate to be gripped. The plate is then wound about the surface of the cylinder and its opposite end is pushed into position between the groove walls 60 and the clamping bars 50, 50 and 52. The three screws 40 mounted in the housings 14 are then operated to rock the said clamping bars into position to grip that end of the plate. Now all of the screws 40 are turned in succession a small amount at a time until the plate approaches the cylinder rather closely, after which the screws 40 in housings 14 are adjusted to effect final tightening of the plate onto the cylinder and to give it any slight variation from absolute parallelism which variation may be required to bring the form into register. Adjustment of the plate lengthwise of the cylinder may be effected at any time before the plate is clamped tightly, or it may be effected thereafter by first loosening the screws 40 holding one or both ends of the plate.

In the form of the invention illustrated in Figs. 9 and 10 any suitable means may be assumed for securing one end of the plate, and this means may be incorporated in a movable housing 70 similar to the housing 13 previously described. Opposite the housing 70 there may be a plurality of housings 71, one only of which is illustrated, these housings being slidable in the gap 72 of the cylinder 73 for the same purpose as in the case of the housings 14. Compression springs 74 tend to separate the housings 70 and 71 in the same manner as described for the first form of the invention.

The plate gripping means for the housing 71 comprises a clamping bar 75 of round cross-section mounted in a groove 96 in the housing,

At least one of the side walls of this groove is inclined so that the groove is constricted somewhat at its mouth. Means are provided for causing bar 75 to tilt or rock about one or more longitudinal fulcrum lines at the bottom of the bar. In the illustrated case this means consists of a pair of pins 76 which take into sockets 77 in the bar, sufficient clearance being provided to permit rocking of the bar about the line joining the points 79. In some cases the bar may also rock about the line joining the points 78. The rocking of the bar may be effected by the operator by means of a pin wrench inserted in the hole 80 through the bar at one end thereof.

In order that an end of plate 81 may be inserted in the clamp the operator rocks or tilts the bar 75 counterclockwise from the position illustrated in Fig. 10, which results in the bar moving away from the inclined wall 82 of the groove. After the end of the plate is inserted the bar 75 is again rocked clockwise to wedge it against the plate 81 and firmly grip the latter. Then a screw 83, similar to the screws 40 of the first described form of the invention, may be threaded into the housing 71 until the end of the screw bears against the wall of the gap, after which further rotation of the screw in the same direction will draw the assembly, comprising bar 75 and housing 71, toward the left as viewed in Fig. 10, thereby drawing the plate into tight engagement with the cylinder surface. When the plate is to be removed the screw is of course turned in the opposite direction, thereby permitting springs 74 to move the clamp assembly outward or toward the gap wall.

In this form of the invention we may provide means for releasably holding the bar 75 in either its operative or inoperative position, which means may comprise a slide 84 mounted in a transverse bore in the housing 71 and having a pocket 85 of a size to loosely engage diametrically opposite points of the bar 75, a socket 86 being formed in the cylinder 73 to receive the end of slide 84 when the latter is in its illustrated position. Two detent sockets 87 and 88 are formed in the slide to receive a detent 89 which is urged downwardly by a coil spring 90. The upper end of this spring bears against a plug 91 threaded into the upper end of the bore in which the detent is mounted to slide. This spring is adapted to yield when the detent is cammed upwardly by the movement of the slide, and the slide in turn is moved when the bar 75 is rocked about the line joining points 79. Housing 71 may be held against radially outward movement by a bolt 92 and washer 93 engaging the top surface of the housing, the shank of the bolt extending down through a hole 94 in the housing of large enough diameter to permit the necessary movement of the housing.

It will be obvious that this form of the invention functions similarly to the functioning of the first described form, in that any strain upon the plate 81 tending to separate it from the clamping assembly merely strengthens the grip of the clamp upon the plate.

Having thus described our invention, we claim:

1. In a plate clamp for use with a cylinder having a gap therein and having means for securing one end of the plate, an elongated housing adapted to be mounted in the gap, said housing having a longitudinal groove therein for reception of the opposite end of said plate, a bar in said groove adapted when rocked transversely to be wedged between one wall of the groove and said plate backed by the other wall of the groove,

and interengaging means between the housing and the bar on the side of the groove remote from its plate engaging wall for providing an abutment against which the bar may bear when it is rocked in a direction to increase plate holding pressure.

2. In a plate clamp for use with a cylinder having a gap therein and having means for securing one end of the plate, an elongated housing adapted to be mounted in the gap, said housing having a longitudinal groove therein for reception of the opposite end of said plate, a bar in said groove adapted when rocked transversely to be wedged between one wall of the groove and said plate backed by the other wall of the groove the plate engaging surface of the groove being planar and the plate-engaging surface of said bar being cam shaped, and interengaging means between the housing and the bar on the side of the groove remote from its plate-engaging wall for providing an abutment against which the bar may bear when it is rocked in a direction to increase plate holding pressure.

3. In a plate clamp for use with a cylinder having a gap therein and having means in the gap for securing one end of the plate, an elongated housing mounted in said gap for movement toward and away from the said secured plate end, said housing having a longitudinal groove therein, a bar in said groove adapted when rocked transversely in one direction to be wedged between one wall of the groove and said plate backed by the other wall of the groove, and common operating means for exerting the clamping action of said bar and for moving the housing in the plate tensioning direction.

4. In a plate clamp for use in a cylinder having a gap therein and having means in the gap for securing one end of the plate, an elongated housing mounted to slide in said gap toward and away from the secured end of the plate, said housing having a longitudinal groove therein, a bar in said groove adapted when rocked transversely in one direction to be wedged between one wall of the groove and said plate backed by the other wall of the groove, and common operating means for exerting the clamping action of said bar and for sliding the housing in the plate tensioning direction.

5. In a plate clamp for use with a cylinder having a gap therein and having means in the gap for securing one end of the plate, an elongated housing adapted to be mounted in said gap for movement toward and away from the secured end of the plate, said housing having a longitudinal groove therein, a bar in said groove adapted when rocked transversely in one direction to be wedged between one wall of the groove and said plate backed by the other wall of the groove, and common operating means for exerting force to rock said bar to grip the plate, and thereafter for exerting force through the bar upon said housing to move the latter in the plate tensioning direction.

6. In a plate clamp for use in a cylinder having a gap therein, elongated housings adapted to be mounted in said gap for movement toward and away from each other, said housings having elongated grooves, clamping bars in each of said grooves adapted when rocked transversely in one direction to be wedged between one wall of the groove and said plate backed by the other wall of the groove and common operating means for exerting the gripping action of a bar and moving

the corresponding housing in the plate tensioning direction.

7. In a plate clamp for use with a cylinder having a gap therein and having means in the gap for securing one end of the plate, an elongated housing mounted in said gap for movement toward and away from the said secured end of the plate, said housing having a longitudinal groove therein, a bar in said groove adapted to be rocked transversely for clamping the other end of the plate against one wall of said groove, common operating means for exerting force to rock said bar to grip the plate, and thereafter for exerting force through the bar upon said housing to move the latter in the plate tensioning direction, and spring means for rocking said bar in the opposite direction when the force exerted by said operating means is relieved.

8. In a plate clamp for use with a cylinder having a gap therein and having means for securing one end of the plate, an elongated housing adapted to be mounted in the gap, said housing having a longitudinal groove therein, a bar disposed longitudinally in said groove adapted to be rocked transversely, said housing being adapted to receive and hold the other end of the plate between said bar and a wall of the groove, said bar having opposed cam surfaces, the distance between the low spots of said cam surfaces being less than the width of said groove minus the thickness of the plate and the distance between the high spots being greater than the width of the groove minus the thickness of the plate, whereby the rocking of the bar in one direction causes the plate to be gripped between the bar and the housing and the rocking of the bar in the opposite direction releases the plate.

9. In mechanism of the character described, an elongated housing having a longitudinal groove therein, a bar disposed longitudinally in said groove adapted to be rocked transversely, said housing being adapted to receive and hold one end of a printing plate between said bar and a wall of the groove, the plate engaging surface of the bar being cam shaped and interengaging means between the housing and the bar on the side of the groove remote from its plate-engaging wall for providing an abutment against which the bar may bear when it is rocked in a direction to increase plate holding pressure.

10. In plate clamping means, a housing having a groove therein formed with oppositely disposed walls, said groove being adapted to receive the end of the plate to be clamped, a bar in said groove adapted when rocked transversely in one direction to be wedged between one wall of the groove and said plate backed by the other wall of the groove, and when rocked in the opposite direction to release said plate, and means operative when the bar is turned in the plate clamping direction to prevent slipping of the bar on the first said wall in a direction to cause release of said plate.

11. In plate clamping means, a housing having a groove therein formed with oppositely disposed walls, said groove being adapted to receive the end of the plate to be clamped, a bar in said groove adapted when rocked transversely in one direction to be wedged between one wall of the groove and said plate backed by the other wall of the groove, and when rocked in the opposite direction to release said plate, means operative to prevent slipping of the bar on said first named

wall in a direction to cause release of said plate, and means to selectively retain said bar in plate clamping or plate releasing position.

12. In plate clamping means, a housing moveable in plate loosening and plate tensioning directions, spring means tending to move said housing in the plate loosening direction, said housing having a groove therein formed with oppositely disposed walls, said groove being adapted to receive the end of the plate to be clamped, a bar in said groove adapted when rocked transversely in one direction to be wedged between one wall of the groove and said plate backed by the other wall of the groove, and when rocked in the opposite direction to release said plate, spring means tending to turn said bar in its plate releasing direction, and positive means operable by engagement with said bar to turn the latter in plate clamping direction against the resistance of its spring and thereafter to move the housing in the plate tensioning direction against the resistance of said first named spring.

13. In mechanism of the character described, an elongated housing having a longitudinal groove therein, a bar in said groove having a cam surface adapted when the bar is rocked transversely to wedge the bar between one wall of the groove and an end of a printing plate backed by the other wall of the groove, said housing being movable bodily for plate tensioning purposes, and common operating means for exerting the clamping action of said bar and for moving the housing in the plate tensioning direction.

14. In mechanism of the character described, an elongated housing having a longitudinal groove therein, a bar in said groove adapted when the bar is rocked transversely to be wedged between one wall of the groove and a printing plate backed by the other wall of the groove, said housing being movable bodily for plate tensioning purposes, and common operating means for exerting force to rock said bar to grip the plate and thereafter for exerting force through the bar upon said housing to move the latter in the plate tensioning direction.

15. In plate clamping means, a housing having a groove therein formed with oppositely disposed walls, said groove being adapted to receive the end of the plate to be clamped, and a bar in said groove adapted when rocked transversely in one direction to be wedged between one wall of the groove and said plate backed by the other wall of the groove, and when rocked in the opposite direction to release said plate, said housing and said bar comprising cooperating abutment means operative, when force is applied to the bar tending to turn it in the plate clamping direction, to prevent displacement of the bar in a direction to cause release of said plate.

16. In plate clamping means, a housing having a groove therein formed with oppositely disposed walls, said groove being adapted to receive the end of the plate to be clamped, a round bar in said groove adapted when rocked transversely in one direction to be wedged between one wall of the groove and said plate backed by the other wall of the groove, and when rocked in the opposite direction to release said plate, said bar and said housing being provided with cooperating abutment means about which said bar may be rocked.

CHARLES W. HARROLD,
EARL W. CURTIS.
